RECLOSING CIRCUIT BREAKER

Paul B. Parks, Oak Park, Ill., assignor to Vapor
Car Heating Company, Inc., Chicago, Ill., a
corporation of New York

Application October 12, 1934, Serial No. 748,096

4 Claims. (Cl. 175—294)

This invention relates to certain new and useful improvements in reclosing circuit-breakers, and also to an improved safety circuit controlled by this circuit breaker so as to prevent the too prolonged flow of a destructive current through the circuit and thus protect electrically actuated devices in this circuit.

As is well known, the flow of an abnormal current in an electric circuit, caused by an overload or a short circuit may cause damage to the electrical apparatus in the circuit. Also some electrical devices are adapted to be actuated by a rather heavy current which flows only momentarily and is then cut off. If this current were allowed to flow for too long a time the apparatus would be injured. To prevent this, fuses or automatic circuit-breakers are often provided in the circuit. A fuse will burn out and must be replaced before the circuit can be reestablished. Many circuit breakers are of the type which must be manually reset before the circuit can be reestablished. According to the present invention, the improved circuit-breaker is of the type which is automatically re-closed at intervals, so that if the abnormal condition is only temporary the circuit will be automatically reestablished. An apparatus of this general type is disclosed and claimed in the patent to Parks et al. #1,922,452, granted August 15, 1933. The present invention relates to improvements in an apparatus of this type, as hereinabove set forth. Also, according to the present invention, the main operating circuit is not entirely broken, but a high-resistance signal device is thrown into the circuit when the circuit-breaker is open. This high-resistance device functions to cut down the current flow to such an extent that the apparatus will not be injured, and at the same time gives a visible or audible signal so that the attendant will become aware of the abnormal condition and take steps to correct the same.

Briefly described, the controlling mechanism comprises a self-closing, normally closed circuit-breaker in the main circuit, and an electromagnetic device which will open the circuit breaker when energized. A heating element included in the main circuit is positioned adjacent a thermostatic device within a closed heating chamber. The prolonged passage of a heavy current through this heating element will affect the thermostatic device so as to close a switch which completes a circuit through the electromagnetic device thus opening the circuit breaker. The closing of the switch also completes an energizing circuit for an electromagnet which tends to hold the switch

closed so as to delay the re-closing of the main circuit for a more or less predetermined length of time.

The principal object of this invention is to provide an improved overload safety circuit of the type briefly described hereinabove and disclosed more in detail in the specifications which follow.

Another object is to provide an improved reclosing circuit-breaker including electromagnetic means for opening the circuit and delaying the re-closing of the circuit.

Another object is to provide an improved means for automatically throwing a high-resistance signal device into a circuit so as to reduce the current flow and give an indication of the abnormal operating conditions.

Other objects and advantages of this invention will be more apparent from the following detailed description of one approved form of apparatus constructed and operating according to the principles of this invention.

The accompanying drawing is a diagrammatic illustration of the improved circuits and the improved safety mechanisms included therein.

The combination shown includes generally a source of electric power A (here shown by way of example as a battery), a pair of electrically operated valves B and B', a pair of relays C and C' for controlling the actuating circuit for the valves B and B' respectively, a pair of temperature responsive mechanisms D and D' respectively controlling the relays C and C', the re-closing circuit breaker E, the assembly F for controlling the circuit-breaker, and the signal device G.

The valves B and B' are similar and of the type commonly in use for controlling the flow of steam through the radiators of a railway car heating system. Each valve is controlled by a handle 1, pivoted intermediately at 2, the valve being shown in the closed position. When handle 1 is swung to an oppositely inclined position at the other side of the vertical, the valve will be open. A pair of electric motor mechanisms 3 and 4 are provided for respectively moving the valves to open and closed position. As here shown these motors are in the form of solenoids 3 and 4 having their respective cores 5 and 6 carried at the ends of an operating rod 7 having an intermediate yoke 8 which engages one arm of the handle or lever 1. When solenoid 4 is energized, the handle will be swung to the position shown in the drawing and the valve will be closed. When solenoid 3 is energized, the handle will be swung to an oppositely inclined position and the valve will be open. A snap-switch 9, 55

actuated by a yoke 10 on the opposite end of lever 1, comprises a movable contact 11 adapted to engage alternatively with the fixed contacts 12 and 13. The purpose of this snap-switch is to break the operating circuit of solenoid 3 or 4 as soon as the valve movement has been completed. A rather heavy current is used in the motor, and if the flow of this current was allowed to persist for too long a time damage 10 might be done to the electrical mechanism. This flow of current will normally be cut off by the snap-switch 9 as soon as one of the valve movements has been completed, but in case the valve should stick or some other abnormal condition 15 should arise, the snap-switch 9 might fail to break the circuit at this point and the continued flow of current might prove to be destructive. To prevent this, the safety mechanisms E, F and G, hereinafter described, are provided.

20 The relay C is normally energized through the following closed circuit: from positive main 14 through wires 15 and 16, resistance 17, relay coil 18, wire 19, resistance 20, and wire 21 to the negative main 22. When so energized, the movable contact plate 23 will be pulled down into engagement with the pair of fixed contacts 24 and 25. The thermostatic mechanism D is adapted to short circuit this current around the coil 18 so as to deenergize the relay and permit the 25 spring 26 to move the contact plate 23 into engagement with the pair of fixed contacts 27 and 28 (as shown in the drawing).

This thermostatic mechanism D is of a well known type comprising a plurality of mercury tube thermostats 29, 30 and 31 adapted to function respectively at certain predetermined high, medium, and low temperatures, the thermostat in control of the relay at any given time being determined by the positioning of the manually 30 operated selector switch 32. This switch comprises a movable contact arm 33, always in engagement at its lower end with the arcuate contact plate 34, and adapted to be moved selectively into engagement at its upper end with any one 35 of the fixed contacts 35, 36 or 37. As shown in the drawing, the low temperature thermostat 31 is in control of the relay. When the mercury column 38 of this thermostat rises sufficiently to engage the fixed contact 39, a shunt circuit 40 around the relay coil 18 will be completed as follows: from one terminal of this relay coil through wire 40, thermostat 31, wire 41, fixed contact 37, movable contact arm 33, fixed contact 34, and wire 43 to the other terminal of coil 18. This 45 will deenergize the relay and permit spring 26 to move the contact plate 23 to the position shown in the drawing. When the temperature in the space whose temperature is to be controlled by the mechanism D falls below the predetermined temperature for which thermostat 50 31 is adjusted, the mercury column will break this circuit by moving down out of contact with the fixed contact member 39 so that this shunt circuit will be broken and the relay coil 18 will 55 again be energized so as to draw the contact plate 23 down into engagement with the lower contacts 24 and 25. When the movable selector arm 33 is moved into a vertical position in engagement with the fixed contact 36, an exactly 60 similar control circuit will be completed through the medium temperature thermostat 40, but at a somewhat higher temperature. When contact arm 33 is moved into engagement with the contact 35, the control circuit will be completed at 65 a still higher temperature through wire 40, ther-

mostat 29, and wires 44 and 43 directly back to the relay coil.

The circuit-breaker E comprises the movable contact plate 45 which is normally held by spring 46 so as to bridge the two fixed contacts 47 and 48. When the electromagnetic device 49 is energized, the movable contact plate 45 will be drawn down into engagement with the stops 50 so as to break the circuit between contacts 47 and 48. The control mechanism F, which will be hereinafter described more in detail, includes a heating element 51 (usually a resistance coil) which will become rather highly heated when the normal operating current for the valves B or B' flows therethrough for any unusual length of 15 time.

Returning now to the operation of the valve mechanisms, the valve B is shown in the drawing as closed, the temperature in the space to be heated having risen to or above the predetermined temperature for which thermostat 31 is adjusted. When the temperature in this space falls below the predetermined temperature, the shunt circuit through thermostat 31 will be broken and relay C will again be energized so 20 as to pull down the contact plate 23, whereupon an operating circuit for opening the valve B will be completed as follows: from positive main 14 through wires 15 and 52, relay contacts 24, 23 and 25, wire 53, solenoid 3, wire 54, snap-switch 30 contacts 12 and 11, wires 55, 56 and 57, circuit-breaker contacts 48, 45 and 47, wire 58, heating element 51 and wire 59 to the negative main 22. Solenoid 3 will now draw in the core 5 and move the valve to open position, and at the completion of this movement the actuating circuit will be broken by snap-switch 9 moving the contact 35 11 over into engagement with the other fixed contact 13. When the temperature again rises to the predetermined point, the shunt circuit 40 through thermostat 31 will again be completed so as to deenergize the relay C, whereupon relay contact plate 23 will again be moved up into engagement with fixed contacts 27 and 28 thus 45 completing an actuating circuit for valve motor 4 as follows: from positive main 14 through wires 15 and 60, relay contacts 27, 23 and 28, wire 61, solenoid 4, wire 62, snap-switch contacts 13 and 11, and thence as before through wires 55, 56 and 57 to and through the circuit-breaker E and 50 heating element 51. As soon as the valve has been moved to closed position, this circuit will be broken by snap-switch 9 moving contact 11 back into engagement with contact 12, all as shown 55 in the drawing.

The valve mechanism B' may be controlled in an exactly similar manner through relay C' by means of the single thermostat D'. It will be noted that all of these valve-actuating circuits pass through the circuit-breaker E and the heating element 51. It will also be understood that the valve operating assemblies B and B', as well as their control mechanisms C and C' and D and D' are shown and described principally for the purpose of illustrating a type of electrically-60 operated apparatus that may be protected by the improved safety mechanisms E, F and G.

The control assembly F comprises the casing 63 provided with closure 64 so as to completely inclose the heating chamber 65 in which is positioned the heating coil 51 connected between the two terminals or binding posts 66 and 67 with which the wires 58 and 59 are respectively connected. A suitable thermostatic element is also housed within this casing, closely adjacent to the 75

heating element 51, so as to respond quickly to temperature changes produced by the prolonged flow of current through the coil 51. Preferably this thermostatic element is in the form of a bimetallic bar 68 anchored at one end 69 in the casing and in electrical connection with binding post 67. A movable contact 70 carried by the free end of bar 68 is adapted to engage with fixed contact 71 mounted in the casing wall so as to form a normally open switch. When the bar 68 is heated, it will warp downwardly so as to bring switch contact 70 into engagement with the fixed contact 71. The armature 72 of an electromagnet 73 is mounted in the lower wall of casing 63 so as to be in position to attract and hold the bar 68 in its warped position when the electromagnet is energized. This magnet is not of sufficient strength to permanently hold the thermostatic bar in this warped position, but it will resist the tendency of the bar to straighten out so that the thermostatic bar must cool considerably before it can move away from the magnet and break the switch contacts.

The signal device G is in the form of an electric lamp, or other visible or audible signal device of rather high resistance, connected through wires 74 and 75 in a branch of the main circuit in parallel with or shunted around the circuit closure contacts 47 and 48.

Assuming now that one of the valve mechanisms B or B' should stick, or some other abnormal condition should arise so as to cause one of the heavy operating currents to persist for an abnormal length of time, the heating element 51 will become heated sufficiently to cause the thermostatic bar 68 to warp downwardly and close the switch contacts 70 and 71 so that an energizing circuit for electromagnet 49 will be completed as follows: From positive main 14 through wire 74, electromagnetic device 49, wire 75, switch contacts 71 and 70, thermostatic bar 68, binding post 67, and wire 59 to the negative main. This will energize the electromagnetic device 49 and draw down the contact plate 45 so as to break the main operating circuit between contacts 47 and 48. This main circuit will not be entirely broken but will now be shunted through the high resistance signal device G. This device G will now be illuminated or will give other indication to the attendant that some abnormal condition exists, and at the same time it will so cut down the current flowing in this main circuit that it will no longer be injurious to the valve-operating mechanism, nor will it be sufficiently strong to highly heat the element 51 which will now begin to cool off. At the same time an energizing circuit for the holding magnet 73 will be completed as follows: From positive main 14 through wires 74 and 76, magnet 73, wire 73', switch contacts 71 and 70, thermostatic bar 68, binding post 67, and wire 59 to the negative main. This magnet will tend to hold the switch in closed position, and will prevent chattering of the switch. As soon as the thermostatic bar 68 begins to cool off it will tend to straighten out and break the energizing circuit through the switch, but the magnet 73 will tend to hold the switch in closed position for a certain time before the thermostatic bar develops enough energy to break the switch contacts. Also the housing of the heating element 51 and thermostat 68 within the closed casing tends to delay the loss of heat from these elements and thus delay the re-closing of the circuit-breaker and the main operating circuit, and cause the signal D to operate for a suitable length

of time. After a certain time, the thermostat 68 will cool off sufficiently to overcome the attraction of magnet 73 and break the switch contact thereby deenergizing the electromagnets 73 and 49, and the circuit-breaker will again be closed by spring 46 thus short-circuiting the signal G and again completing the normal operating system. If by this time the abnormal condition in this operating circuit has ceased to exist or has been corrected, the devices E, F and G will remain in this normal position (as shown in the drawing), but if the main circuit is still closed the element 51 will again heat up so as to cause another movement of the thermostatic bar and the operations previously described will be repeated so as to again open the circuit-breaker and cause the signal G to operate. This cycle of events will be continued indefinitely until the main operating circuit is broken at some other location, by the proper operation of the snap switches 9, or some equivalent operation in case other types of mechanism are positioned in this circuit.

By inclosing the heating element 51 and thermostat 68 in close juxtaposition within the airtight casing 63, the heating element and bar will heat up quickly when subjected to an abnormal current flow, and also the slow dissipation of heat from this heating chamber 65 will help to delay the re-closing of the circuit-breaker for a desired time interval.

I claim:

1. In combination with a main circuit, a normally closed circuit-breaker in this circuit, and an electromagnetic device adapted to open the circuit-breaker and thereby break the main circuit, a thermostatic-switch assembly comprising an electric-heating element, a thermostatic element positioned in close proximity to the heating element, a casing intimately enclosing the heating and thermostatic elements to form a closed heating chamber about these elements so as to expedite the transfer of heat therebetween and minimize the heat losses from the thermostat, a switch mounted in the casing and adapted to be closed by the thermostat when heated, electric terminals for the heating element and switch carried by the casing, the heating element being connected in the main circuit, an electro-magnetic device mounted on the casing and having an armature projecting through a wall of the casing into position to attract the thermostatic element and hold the switch closed while the thermostat is heated, and energizing circuits for the two electromagnetic devices, both of said circuits including the switch and being opened and closed thereby.

2. In combination with a main circuit, a normally closed circuit-breaker in this circuit, and an electromagnetic device adapted to open the circuit-breaker and thereby break the main circuit, the main circuit including a branch shunted around the circuit-breaker, and a high-resistance signal device in said branch circuit, a thermostatic-switch assembly comprising an electric-heating element, a thermostatic element positioned in close proximity to the heating element, a casing intimately enclosing the heating and thermostatic elements to form a closed heating chamber about these elements so as to expedite the transfer of heat therebetween and minimize the heat losses from the thermostat, a switch mounted in the casing and adapted to be closed by the thermostat when heated, electric terminals for the heating element and switch carried by the casing, the heating element being

connected in the main circuit, an electromagnetic device mounted on the casing and having an armature projecting through a wall of the casing into position to attract the thermostatic element and hold the switch closed while the thermostat is heated, and energizing circuits for the two electromagnetic devices, both of said circuits including the switch and being opened and closed thereby.

- 10 3. In combination with a main circuit, a normally closed circuit-breaker in this circuit, and an electromagnetic device adapted to open the circuit-breaker and thereby break the main circuit, a thermostatic-switch assembly comprising 10
15 a casing enclosing a shallow heating chamber, a heating element mounted within this chamber, a thermostatic bar anchored at one end in a wall of the casing and projecting into the chamber in proximity to the heating element, a
20 movable switch contact carried by the free end portion of the bar, a second switch contact mounted in one wall of the casing in position to be engaged by the movable contact when the bar is heated, and terminals mounted in the
25 casing and connected respectively with the ends of the heating element, the fixed end of the bar, and the fixed switch contact, the heating element being connected in the main circuit, an electromagnetic device mounted on the casing and having an armature projecting through a
30 wall of the casing into position to attract the bar and hold the switch closed while the bar is heated, and energizing circuits for the two elec-

tromagnetic devices, both of said circuits including the switch and being opened and closed thereby.

4. In combination with a main circuit, a normally closed circuit-breaker in this circuit, and an electromagnetic device adapted to open the circuit-breaker and thereby break the main circuit, the main circuit including a branch shunted around the circuit-breaker, and a high-resistance signal device in said branch circuit, a thermostatic-switch assembly comprising a casing enclosing a shallow heating chamber, a heating element mounted within this chamber, a thermostatic bar anchored at one end in a wall of the casing and projecting into the chamber in proximity to the heating element, a movable switch contact carried by the free end portion of the bar, a second switch contact mounted in one wall of the casing in position to be engaged by the movable contact when the bar is heated, and terminals mounted in the casing and connected respectively with the ends of the heating element, the fixed end of the bar, and the fixed switch contact, the heating element being connected in the main circuit, an electromagnetic device mounted on the casing and having an armature projecting through a wall of the casing into position to attract the bar and hold the switch closed while the bar is heated, and energizing circuits for the two electromagnetic devices, both of said circuits including the switch and being opened and closed thereby.

PAUL B. PARKS.
